UNITED STATES PATENT OFFICE.

NAPOLEON DU BRUL, OF CINCINNATI, OHIO.

DESIGN FOR A FRAME FOR CIGAR-BUNCHING MACHINES.

SPECIFICATION forming part of Design No. 23,703, dated October 16, 1894.

Application filed March 2, 1894. Serial No. 502,143. Term of patent 14 years.

To all whom it may concern:

Be it known that I, NAPOLEON DU BRUL, a citizen of the United States, residing at Cincinnati, in the county of Hamilton and State of Ohio, have invented and produced a new and original Design for a Frame for Cigar-Bunching Machines, of which the following is a specification, reference being had to the accompanying drawing, showing a perspective

view thereof.

The leading features of my design consist in a vertical transverse plate having a cylindrical portion at the lower end and a cylindrical portion at the inner side, the horizontal plate, crossing the vertical plate, having a surmounting shoulder at its inner end, and a convex plate, crossing the upper end of the vertical plate, having a trough shaped outer portion.

1 represents a vertical transverse plate hav-

ing a cylindrical portion at its lower end and a cylindrical portion on the inner side near its lower end. Crossing the upper portion of the vertical plate is a horizontal plate 3 having a surmounting shoulder 3^a, at its inner 25 end.

2 is a convex plate crossing the upper end of the vertical plate having a trough shaped outer portion 2^a.

Having thus described my invention, the 30 following is what I claim as new therein and desire to secure by Letters Patent:

The design for a frame for cigar bunching machines substantially as herein shown and described.

NAPOLEON DU BRUL.
